ROTARY WING AIRCRAFT

Peter J. Papadakos, St. James, N.Y., assignor to Gyro-dyne Company of America, Inc., St. James, N.Y., a corporation of New York

Application October 16, 1956, Serial No. 43,370

Term of patent 14 years

(Cl. D71—1)

Figure 1 is a front perspective view of a rotary wing aircraft, showing my new design.

Figure 2 is a rear perspective view.

The opposite side is like that appearing in the drawing except that there is no door opening.

I claim:

The ornamental design for a rotary wing aircraft, as shown and described.
